TIMOTHY F. COUGHLIN, OF JERSEY CITY, NEW JERSEY.

SEAL.

1,181,743.

Specification of Letters Patent.

Patented May 2, 1916.

Application filed February 10, 1915. Serial No. 7,278.

To all whom it may concern:

Be it known that I, TIMOTHY F. COUGHLIN, a citizen of the United States, and a resident of Jersey City, in the county of 5 Hudson and State of New Jersey, have invented a new and Improved Seal, of which the following is a full, clear, and exact description.

This invention relates to improvements in 10 seals used in sealing the locks of cars, safes, and in fact any other desired device which it is desired to seal against opening by anyone, and has for an object to provide an improved structure which must be broken before the same can be removed.

Another object in view is to provide a seal formed of wire having a looped end through which the loose end of the wire is adapted to be threaded when placing the seal in use.

20 A further object of the invention is to provide a seal formed of lead or similar material, and of wire, and so arrange the embedded end of the wire that one or more loops are utilized and arranged to surround 25 the aperture through which the free end of the wire is passed when placing the seal in position so that upon the pressing or collapsing of the seal, loops will become interlocked with the loose end of the wire and 30 thus prevent positively any movement thereof.

In the accompanying drawings—Figure 1 is a fragmentary view of a car showing a lock provided with a seal embodying the invention; Fig. 2 is a front view of a seal embodying the invention; Fig. 3 is a perspective view of the embedded end of the wire with the lead shown in dotted lines; Fig. 4 is a section through Fig. 2 on line 4—4, the 40 same being on an enlarged scale; Fig. 5 is a view similar to Fig. 4 but showing the relation of the loops with the body of the wire when the lead is partly compressed.

Referring to the accompanying drawings by numerals, 1 indicates a car of any desired construction and 2 a lock also of any desired construction. Entwined in the lock 2 is the usual wire 3 of the seal 4, both ends of the wire 3 being embedded in the seal 4 50 when the same is properly placed in position and pressed by the usual form of pliers. In some forms of seals which have been used heretofore the lead is merely pressed around the wire which will hold the same 55 unless some movement is given the wire, whereupon the wire will gradually work

loose and thus make the seal of no effect. The present invention is intended to overcome this objection by the provision of one or more loops 5 (Fig. 3) arranged in the 60 end of the wire 3 which is permanently embedded in the lead body 6. These loops are intended to fit around the aperture or hole 7 in body 6 so that when the loose end 8 of the wire 3 is threaded through aperture 7 65 and then the body 6 collapsed as shown in Fig. 5, the loops or coils 5 will be pressed downwardly and caused to interlock with the various parts of wire 3. Wire 3 is preferably a wire having a plurality of strands, 70 as for instance a wire having a large central strand 9 and one or more auxiliary strands 10 which provide raised portions. These raised portions present projections or means for allowing not only the interlocking of 75 the loops 5 but of the lead forming the body 6. The aperture 7 is preferably inclined as shown in Fig. 4. By this construction and arrangement it will be observed that both ends of the wire are interlocked in such a 80 way as not to be readily disengaged even though the body 6 was eliminated.

It will be evident that the seal may be used at any desired place and not only for car locks. The idea intended is to provide a seal which positively cannot be opened and then again closed without detection. By arranging the loops as shown in Fig. 3 so that they will be embedded as shown in Fig. 4, an interlocking or intermeshing of the wire 90 will result as shown in Fig. 5, which in turn will prevent even an authorized person from removing the seal unless the same is broken. A back and forth movement of the end 8 of the sealing wire will not be sufficient to loosen the wire so that the same may be removed as in the case of an ordinary lead seal.

In forming the body 6 preferably lead is used or some similar material, but it will be 1 evident that other materials could be used instead of lead without departing from the spirit of the invention provided they had substantially the same characteristics, and the expression "lead" in this specification is 1 to be understood as covering several substitutes.

What I claim is—

A seal of the character described, comprising a sealing wire formed from a central 1 enlarged wire and extra wires wrapped around the central enlarged wire, the loops

- of the extra wires being spaced apart so as to provide raised portions, said sealing wire being formed with a plurality of loops, a soft metal body surrounding said loops, said 5 soft metal body being provided with an opening extending through said loops for receiving a loose end of said wire, said opening and the general direction of said loops being at such an angle that one end of 10 the opening and one end of the loops will be nearer one end of said body than the other, whereby when said soft metal body and

said loops are crushed or pressed the loops will become interlocked with the raised portions of said wire for providing a lock which ¹⁵ cannot be worked loose.

In testimony whereof I have signed my name to this specification in the presence of two subscribing witnesses.

TIMOTHY F. COUGHLIN.
